UNITED STATES PATENT OFFICE.

STEPHAN PODMAYER, OF ST. LOUIS, MISSOURI, ASSIGNOR TO STABILITY LEATHER
GOODS MFG. CO., OF ST. LOUIS, MISSOURI, A CORPORATION OF MISSOURI.

BAGGAGE LOCK.

Application filed February 2, 1925. Serial No. 6,189.

This invention relates to devices by which suitcases or other baggage may be sealed, so that they cannot be opened without breaking the seal.

5 The principal object of the present invention is to provide the lock of the suit-case or other baggage with means for enabling a sealing device to be easily and quickly attached to the suit-case. Other objects are 10 simplicity and cheapness of construction and compactness of design.

The invention consists principally in providing the cooperating members of a suitcase lock with means adapted, in the closed 15 position of the lock, to be secured together by a sealing device adapted to be broken by opening the bag. The invention also consists in the parts and in the combinations and arrangements of parts hereinafter described 20 and claimed.

In the accompanying drawing which forms part of this specification and wherein like symbols refer to like parts wherever they occur,

25 Fig. 1 is a top view of a portion of a suitcase equipped with a hasp-lock provided with means embodying my invention, by which the lock may be sealed;

30 Fig. 2 is an end elevation of a suitcase showing the swinging hasp disengaged from the lock mechanism;

Fig. 3 is a face view of a lock casing; and

Fig. 4 is a similar view of the outer end portion of the swinging hasp.

35 Referring to the accompanying drawing, my invention is shown in connection with a hasp lock A for securing together the two hinged sections of a suitcase or other baggage B. The hasp lock comprises a lock casing 5 and a hasp member 6 secured to the respective hinge sections adjacent to their meeting edges. The lock casing supports a lock mechanism comprising a spring projected bolt 7 adapted to be retracted by 40 means of a pushblock 8, except when it is locked with a key (not shown) adapted to be inserted in a key-hole 9 provided therefor in said push-block. The bolt 7 has a beveled end portion adapted, in the projected position of the bolt, to extend into a

slot or opening 10 formed in the lock casing; and the swinging hasp member 6 of the lock is provided on its under side with a keeper 11 arranged to enter said slot and engage the beveled end of said bolt, which slides or 55 catches in an opening provided therefor in said keeper. This construction of hasp-lock is well known and it is considered unnecessary to illustrate it in detail.

The swinging hasp 6 of the hasp-lock is 60 provided adjacent to the keeper 11 with an elongated slot 12 adapted, in the closed position of the lock, to receive an apertured outstanding ear or lug 13 on the lock casing 5 adjacent to one margin of the slot 10, which 65 secures the aperture and keeper 11 on the swinging hasp 6. The lock is sealed by extending a shackle, preferably in the form of a wire, band, or cord 14, through the opening in the ear or lug 13 on the lock casing 5 at a point located above the swinging hasp 6 and securing the free ends of the shackle by a seal, preferably in the form of a compressible or deformable disk 15. 70

75 From the foregoing description, it is obvious that my invention provides a cheap, simple and compact device by which the suitcase lock may be easily and quickly sealed so that the lock cannot be opened without breaking or rupturing the seal, thus 80 indicating whether the lock has been tampered with.

What I claim is:

A hasp lock comprising a lock casing having a spring projected bolt therein extending into a slot in said casing, and a swinging hasp having an apertured keeper adapted to enter the slot in said lock casing and engage the bolt therein, one marginal portion of said slot being formed with an outstanding apertured ear and said hasp being formed adjacent to the apertured keeper thereof with an opening adapted to receive with the outstanding ear on said lock casing said apertured ear being formed by bending out a portion of the metal removed from said slot. 85 90 95

Signed at St. Louis, Missouri, this 30th day of January, 1925.

STEPHAN PODMAYER.
